UNITED STATES PATENT OFFICE.

ANNA O'BRIEN, OF NEW YORK, N. Y.

APPARATUS FOR WAVING HAIR.

Application filed August 27, 1926. Serial No. 131,832.

The present invention relates to devices for use in dressing hair.

The invention provides apparatus which can be easily applied to the hair without requiring the service of a skilled hairdresser, and which will produce a wave that can be attractively arranged in dressing the hair.

The apparatus when applied to bobbed hair can be arranged to cause the ends of 10 the hair to be turned in, if desired, thus facilitating dressing of the hair in certain popular styles.

The nature and objects of the invention will be better understood from a consideration 15 of a particular illustrative embodiment thereof for the purpose of which description reference should be had to the accompanying drawing forming a part hereof and in which—

20 Figure 1 is a rear view showing one of the clamps forming a part of an apparatus embodying the invention.

Figure 2 is a side view of the same.

25 Figure 3 is a front view thereof.

Figure 4 is a rear view of a form forming a part of the apparatus and about which the hair is clamped in the use of the device.

Figure 5 is a side view of the form shown in Figure 4.

30 Figure 6 is an end view of the clamp.

Figure 7 is an end view of the form.

Figure 8 is a side view showing a heating member arranged to be inserted within the form.

35 Figure 9 is a sectional view of the same taken on the line 9—9 of Figure 8, and

Figure 10 is a view showing the apparatus embodying a plurality of forms and cooperating clamps applied to the hair together 40 with heating elements applied within the forms.

The apparatus shown for the purpose of illustrating the invention comprises a series of similar hair waving devices each comprising an inner form 5 about which the hair is trained and an outer clamp 6 partially or entirely surrounding the form to hold the hair there against. A heating element 7 may be provided if desired and as shown is 45 arranged to be inserted within the form 5 which is made hollow for this purpose.

The heating elements 7 are preferably made hollow or of tubular form as best shown in Figure 9. By making the heating 50 elements of this form they may be made of relatively large diameter to substantially fill

the tubular forms and at the same time they may have relatively small mass of metal thus avoiding accidental overheating of the forms. The thin walled heating element 60 cools rapidly and therefore even if red hot when introduced into the tubular form will cool without burning the hair.

It is convenient, in use, to apply the inner members or forms to the hair in the desired 65 spaced relation and thereafter to apply the clamping members to bind the hair around the forms. In order to facilitate application of the forms and to hold them in place on the hair each form is provided with a retaining element or clamp 9 hinged adjacent one end and arranged to snap into retaining engagement with the other end as indicated at 10. As shown the forms consist of tubes, two apertures being provided at one end to 70 provide a hinge connection for the retaining clamp 9. The opposite end of the tube is formed with a projection 10 which is engaged by a hook 11 on the free end of the clamp 9.

Each clamp is formed with opposed 75 spring pressed jaws 12 arranged to embrace and substantially fit around the form to hold the hair therearound. The clamp shown is of simple construction such that the parts 80 thereof may be stamped from sheet metal, each stamping presenting a curved embracing jaw 12 and a rearwardly projecting handle portion 13. The handle portions are bent to provide ears 14, which facilitate connection of the two members by a pivot pin 15. Each stamping is preferably stiffened by a rib 16 struck up between the handle portion and the jaw 12.

The two jaws may be of identical shape, the ears 14 being overlapped with one ear of one jaw outside of the corresponding ear of the other jaw and the second ear of the first jaw inside of the corresponding ear of the second jaw or they may be formed as shown with the ears of 90 one spaced further apart to receive the more closely spaced ears of the other jaw therebetween. A double spring 18 encircles the pivot pin and engages the handle members to force the same apart thereby to close the 95 jaws. The forward edges of the jaws are curved inwardly thereby presenting curved edges toward the hair which tend to draw the strand of hair together at the edge of the clamp and keep it away from the ends 100 of the form and clamp and therefore away from the projecting heating iron.

In the use of the described apparatus the forms 5 are applied to a strand of hair in spaced parallel relation each form being retained upon the hair by means of the retaining element 9 which is placed over the strand of hair and the end snapped into engagement with the form. If it is desired to have the ends of the hair curved inwardly, care is taken that the ends of the strand of hair 10 engaging the clamping member adjacent the end of the strand are turned well around the form and that the clamp member is so positioned on the form as to hold the ends under. After the forms and clamps are all in 15 position, the heating irons are inserted into the hollow forms.

When the apparatus is used for waving long hair the method of application is the same as above indicated but ordinarily it is 20 not desired to place one of the clamps at the end of the hair or to turn in the ends as in the case of certain styles of dressing bobbed hair.

The apparatus shown may also be used for 25 waving hair without the application of heat, the hair being dampened and the apparatus being left applied to the hair for a longer period of time.

It will be understood that the description 30 of the particular embodiment of the invention is illustrative merely and is not intended as defining the limits of the invention.

I claim:

1. Apparatus for use in waving hair com-

prising a tubular member, a retaining member hinged to one end thereof and arranged to snap into retaining engagement with the opposite end to clamp hair against said tubular member, and a spring clamping member arranged to embrace said tubular 40 member to hold hair thereabout, said clamping member comprising two semi-cylindrical members hinged at one edge. 35

2. Apparatus for use in waving hair comprising a tubular member, a retaining member hinged to one end thereof and arranged to snap into retaining engagement with the opposite end to clamp hair against said tubular member, and a spring clamping member arranged to embrace said tubular 45 member to hold hair thereabout, said clamping member comprising two semi-cylindrical members hinged at one edge, and having their free edges curved inwardly toward the center thereof to provide means for bending 50 the hair toward the center of the clamp. 55

3. Apparatus for use in waving hair comprising a hollow tubular member and a separate two-part clamp of substantially the same length as the tubular member arranged to 60 embrace said tubular member to hold the hair in a substantially complete circle about said tubular member.

In testimony whereof, I have signed my name to this specification this 26th day of 65 August.

ANNA O'BRIEN.
